CONTAINER

Filed Sept. 4, 1931

Attorneys

UNITED STATES PATENT OFFICE

ISAAC E. COLVIN, OF BELDING, MICHIGAN, ASSIGNOR TO METAL-GLASS PRODUCTS CO.,
OF BELDING, MICHIGAN, A CORPORATION OF MICHIGAN

CONTAINER

Application filed September 4, 1931. Serial No. 561,168.

The present invention relates to containers and more particularly to means for sealing the mouth of the container.

The main objects of the invention are to provide a novel method of hermetically sealing the opening of a container; to provide novel means for sealing a container having a porcelain finish; and, to provide such sealing means which may be adjustably and detachably secured to the container.

An illustrative embodiment of the invention is shown in the accompanying drawing, wherein:—

Figure 1 is a top plan view of the container and its cap;

Figure 2 is a fragmentary side elevational view thereof;

Figure 3 is a sectional view taken on line 3—3 of Figure 4;

Figure 4 is a sectional view taken on line 4—4 of Figure 5; and

Figure 5 is an enlarged fragmentary sectional view of the upper side of the container and its cap.

It is desirable that containers of the character herein shown and described be provided with a porcelain enamel finish, both for external appearance and for internal acid-resisting qualities. It is likewise desirable that these containers have means whereby the container may be hermetically sealed while in use. Screw caps have heretofore been used which when secured to the container, either leak or if leak-proof, must be screwed so tightly that it is difficult to later remove them. The screw threads likewise rust in time causing the container to leak.

Referring to the drawing in which like parts are designated by the same numerals in the several views, a container 1 is provided with a neck 2 forming a mouth or opening 3 for the container, the neck 2 being provided with a peripheral groove 4.

A springable split ring 5 has an inner peripheral tongue or rib 6 adapted to fit or

seat within the peripheral groove 4 on the neck of the container and a pair of integrally formed outwardly projecting lugs 7, 8 are apertured and screw-threaded respectively to accommodate a screw bolt 9 for tightly securing the ring to the neck of the container.

A cap 10, to which is secured a faucet 11, a valve 12 and a gauge 13, is provided with a plurality of integrally formed laterally projecting bifurcated portions 14 for securing the cap to the container as hereinafter described.

The split ring 5 is likewise provided with a plurality of integrally formed laterally projecting bifurcated portions 15 adapted to register with the bifurcated portions 14 on the cap 10. Screw threaded bolts 16 hingedly secured to the bifurcated portions 15 are adapted to be swung into the registering bifurcated portions 14 of the cap and wing nuts 17 are provided whereby the cap may be adjustably secured to the neck of the container for hermetically sealing the same.

It will thus be seen that a cap is herein shown and described which provides ready and convenient means for hermetically sealing the container.

I claim:

1. In a container having a neck provided with a peripheral groove, a spring metal split ring having a peripheral tongue adapted to detachably slide on said neck and tensionally fit within said groove, and clamps secured to said ring for clamping a cap to said neck.

2. In a container having a neck, a spring metal split ring adapted to slide on said neck, said neck and ring being provided with interlocking tongue and groove elements whereby said ring is tensionally and detachably secured to said neck.
